UNITED STATES PATENT OFFICE.

FRANCIS H. BROWN, OF PHILADELPHIA, PENNSYLVANIA.

AUTOMATIC REGULATING MECHANISM FOR SECONDARY COMBUSTION.

No. 905,844.

Specification of Letters Patent.

Patented Dec. 1, 1908.

Application filed October 4, 1907. Serial No. 395,818.

To all whom it may concern:

Be it known that I, FRANCIS H. BROWN, a citizen of the United States, residing in the city and county of Philadelphia, State of Pennsylvania, have invented a new and useful Automatic Regulating Mechanism for Secondary Combustion, of which the following is a specification.

One of the main objects of my present invention is to devise a regulating mechanism for secondary combustion wherein the volume of air delivered above the fire for secondary combustion varies simultaneously and in proportion to the volume of air delivered beneath the grates for combustion, and the volume of air delivered above the fire is introduced at a predetermined temperature, which latter is maintained substantially constant at all times.

Another object of my invention is to devise a construction in which I may, if desired, introduce into the air passing into the furnace above the fire, steam in its natural or superheated condition, the passage of said steam from the boiler being controlled automatically by the change in steam pressure in the boiler.

Another object of my invention is to provide means for heating to a higher degree, the air passing into the furnace above the fire, which I accomplish in the present instance by providing an additional source of heat for the furnace gases passing through the outer conduit, or a source of heat, electrical or otherwise, in the inner conduit. The rates of combustion are constantly changing and for this reason the volume of air which is passed into the furnace above the fire must vary in proportion thereto, while the temperature of the air which is passed into the furnace above the fire must be of such a degree that all of the unconsumed carbon in the furnace gases will be consumed.

To the above ends my present invention consists of a novel construction of an automatic regulating mechanism for secondary combustion, wherein both the volume or amount and the temperature of air introduced above the fire is automatically regulated and wherein I regulate simultaneously therewith, the draft entering beneath the grates, the temperature of the draft passing above the fire being controlled by an independent source of heat, or by passing

this air conduit through a portion of the furnace.

It further consists of a novel construction of a regulator in which a portion of the draft passing to the grates is deflected therefrom and caused to pass in a suitable conduit through the combustion chamber or other part of the furnace wherein it is heated to a suitable temperature, after which it passes through a conduit opening into the furnace above the fire, said last mentioned conduit being surrounded by a larger conduit through which the furnace gases may pass under certain conditions to the chimney.

It further consists of a novel construction of a regulator in which the heat of the furnace gases is employed to heat the air entering above the fire, the conduit through which said entering air passes being provided with a suitable thermostat or its equivalent, whereby the passage of said furnace gases to the chimney may be automatically controlled.

It further consists of other novel features of construction, all as will be hereinafter fully set forth.

For the purpose of illustrating my invention, I have shown in the accompanying drawings one form thereof since this embodiment gives satisfactory and reliable results in practice, although it is to be understood that the various instrumentalities of which my invention consists can be variously arranged and organized and that my invention is not limited to the exact arrangement and organization of these instrumentalities as herein set forth.

Figure 1 represents a sectional elevation of a furnace showing an automatic regulating mechanism for secondary combustion embodying my invention, in operative relation with respect thereto. Fig. 2 represents a sectional plan view showing more clearly the manner in which the several conduits communicate with the furnace. Fig. 3 represents a sectional plan view showing a modified arrangement in which the air is admitted in front and in rear of the fire as well as at one side thereof.

Similar numerals of reference indicate corresponding parts in the figures.

Referring to the drawings in illustrating my invention I have preferred to show it in conjunction with a furnace which is

provided with an automatic damper regulator such as is described and broadly claimed in my co-pending application for combustion and damper regulator for furnaces, filed April 25, 1907, Serial No. 870,169, since such a construction has been found to give excellent results in practice.

1 designates a furnace provided with grates 2 and a combustion chamber 3.

10 4 designates the boiler which is connected by a conduit 5 with a fan or other draft producing mechanism 6 which latter has a conduit 7 leading to a point beneath the grates 2, said conduit being provided with 15 a valve 8 which is operatively connected with the lever 9 whereby the same may be manually controlled when desired.

10 11, 16 designates a damper in the smoke stack 11, said damper being connected by means 20 of a suitable cable 12 with the regulating mechanism 13 which is actuated by variations in the pressure of the furnace gases, as will be clearly understood from my pending application hereinbefore referred to and to 25 which reference may be had for detailed description thereof.

14 designates a conduit leading from the draft conduit 7 and extending into the combustion chamber 3 as is indicated at 15, Fig. 2, said conduit being bent upon itself in the present instance, as is indicated at 16 and passing out through the furnace wall, although it is to be understood that in the broad scope of my invention it is immaterial in what manner the conduit 15 passes through the combustion chamber 3 or its arrangement therein, since it is only essential that said conduit will extend in such a manner through the combustion chamber or 40 other part of the furnace that it will thereby become suitably heated in order to heat the air passing therethrough. The conduit 16 passes through the side wall of the conduit 17 which communicates with the furnace 45 above the fire, said conduit 17 being also connected with the branch 18 leading to the smoke stack 11. The conduit 16 after passing through the side wall of the conduit 17 opens into an inner conduit 19 which is 50 closed at one end as indicated at 20 and its other end opens through the side wall of the furnace above the grates, it being apparent from Figs. 1 to 3 that this conduit 19 is completely inclosed by the larger conduit 55 17, so that the heated air passing from the conduit 16 through the conduit 19 to the furnace will be heated by the gases passing between said conduit 17 and the conduit 19 to the branch 18 and thereby to the stack 11.

60 In order that the temperature of the furnace gases surrounding the inner conduit 19 will be kept at a uniform or predetermined temperature, I provide in the conduit 17 a damper or valve 21 mounted on a crank arm 65 23 to which a lever 24 is secured, said lever

24 being connected with a bell crank lever 25 pivoted at 26 to a suitable fixed point and provided with a slot 27 in which is adjustably secured one end of the thermostat 28, the opposite end of which is fixedly secured to the bracket 29 carried in any suitable manner by the casing wall, it being noted that the thermostat 28 passes directly through the conduit 19 and the closed end 20 thereof, it being of course understood that this member 26 may be provided with any suitable or conventional type of stuffing box if desired.

In the embodiment seen in Fig. 3, I have shown a slightly modified form of a device in which the conduit 19 is provided with a branch 30 which passes in rear of the fire and is provided with apertures 31 through which the heated air may pass to the flame. I also provide a conduit 32 provided with apertures 33 therein at the front of the fire box, it being noted that the ends of these conduits 30 and 32 are closed in any desired manner. I have shown the form indicated in Fig. 3 for the purpose of illustrating the manner in which the heated air may be passed into the fire box, it being apparent that in the broad scope of my invention it is immaterial whether this heated air is led into the fire box on the side thereof, or at the front or rear thereof.

In some cases it is desirable not to employ a forced or mechanical draft and to this end I employ in the conduit 14 a valve 34 which controls the atmospheric inlet 35 and the passage of air from the conduit 7 to the conduit 14, whereby the conduit 14 will, if desired, communicate with the atmosphere and the conduit 7 with the fire.

In some instances, it is advantageous to employ a connection 36 opening into the outer conduit 17 near its point of entrance to the furnace, said connection communicating with a source of heat 37 which, in the present instance, is shown as a Bunsen burner, although it will be apparent that in the broad scope of my invention, it is simply necessary to increase the temperature of the furnace gases which are passing from the furnace through the outer conduit 17. It is also advantageous in some cases to employ a source of heat near the point of induction of the heated air into the furnace and for this purpose, I have shown as indicated in Figs. 2 and 3, an electric heater 38 located in the inner conduit 19 near the point of entrance to the furnace, so that the heated air passing into the furnace will be further heated by said electric heater, it being understood that this construction has been omitted from Fig. 1 of the drawings for the sake of clearness of illustration. It is also advantageous in some cases to employ a steam connection 39 which communicates with the inner conduit 19 as indicated at 40, said con-

duit being provided with a manually actuated valve 41 and a controlling valve 42, whereby the passage of steam from the boiler to the conduit 19 will vary depending upon the variation in pressure of the steam in said boiler.

In order to superheat the steam passing through the conduit 39, said conduit is passed through a portion of the furnace in any suitable manner, as is clearly indicated in Fig. 1, so that the steam will be superheated to a desired degree before it enters the inner conduit 19.

In order that there will, under all conditions, be produced a sufficiently induced draft in the outer conduit 17, I provide a by-pass 43, which leads to the stack 11, said by-pass being provided with a damper 44 which is carried by the crank arm 23, whereby said damper 44 will be simultaneously actuated with the damper 21.

In the by-pass 43, I locate a blowing mechanism 45 which, in the present instance for the purpose of illustration, I have shown as a fan, actuated by a motor 46 with which communicates the fluid inlet conduit 47, said conduit being provided with an actuating valve 48 to which is connected, one end of a lever 49, the other end thereof being connected to a bell crank lever 50, fulcrumed at 51 to any suitable fixed point and provided with a lever 52 which is connected with the bell crank lever 25, although it is to be understood that my invention in its broad scope comprises a draft producing mechanism in the by-pass 43, which is controlled by the thermostat 28 and any of the usual or conventional types of such draft producing mechanism may be employed.

The operation can now be readily understood and is as follows:—The draft producing mechanism 6 is controlled, in the present instance, by the steam pressure of the boiler and the damper 10 leading from the furnace to the smoke stack is automatically controlled by the variation in pressure of the furnace gases, as will be clearly understood from my pending application to which I have hereinbefore referred and to which reference may be had for the detailed description and operation thereof.

The pull of the stack 11 will cause the air passing through the conduit 7 to be drawn beneath the grates 2, thereby providing for the necessary supply of oxygen for the combustion. The pull of the stack 11 will also cause the air to pass from the conduit 7 through the conduit 14 and therefrom through the conduits 15, 16 and 19, thence into the furnace above the fire, it being noted that the conduits 15 and 16 are located within the furnace in such a manner that the air will become heated as it passes through said conduits.

If the electric heater 38 is in operation,

the air which has become partially heated in the furnace in passing around said heater will become further heated, so that it will enter the furnace above the fire at the necessary temperature to produce the requisite combustion.

The temperature of the air passing through the inner conduit 19 will actuate the thermostat 28 and cause a pull on the bell crank lever 25, so that the crank arm 23 will be actuated and the dampers 21 and 44 will be automatically opened or closed depending upon the temperature of the air in the conduit 19, so that the passage of the furnace gases through the conduit 17 to the branch 18 leading to the stack 11 will be automatically controlled under all conditions.

As seen in Figs. 2 and 3, as the bell crank lever 25 is actuated, it will also exert a pull on the lever 52 thereby actuating the bell crank lever 50 and cause the latter to actuate the lever 49 which controls the valve 48, said valve controlling the admission of fluid pressure through the conduit 47 to actuate the motor 46 which controls the draft producing mechanism 45. It will thus be seen that as the dampers 21 and 44 are partially open, in addition to the pull of the stack, there will be an induced draft in the conduit 43 owing to the provision of the draft producing mechanism 45, whereby the furnace gases will be positively drawn through the outer conduit 17 under all conditions, so that the temperature of the air passing through the inner conduit 19 to the furnace above the fire will be further changed.

When it is desired to inject into the air entering the furnace above the fire, steam in its natural or superheated condition, the controlling valve 41 is opened, whereupon the super-heated steam may pass into the conduit 19, the effect of which is evident.

When it is desired to increase the temperature of the furnace gases passing through the outer conduit 17, I employ a source of heat 37 which communicates by the conduit 36 with the interior of the conduit 17, whereby the temperature of said furnace gases therein may be raised to any desired degree.

It will be apparent that I have illustrated my novel construction of regulating mechanism as employed in conjunction with a well known type of furnace, but the same may be employed in conjunction with any of the usual or conventional types of furnace and substantially the same beneficial results will be obtained. It will also be apparent that I have devised a regulating mechanism wherein I may, irrespective of the type of furnace employed and under the varying conditions met with in practice, pass into the furnace above the fire, a volume of air at a pre-determined temperature, the volume of said air being controlled by a thermostat

actuated by the temperature of said air and the volume varying in proportion to the volume of draft passing beneath the grates.

It will be apparent that while, in the present instance for convenience of illustration, I have shown the conduits 17 and 19 and their adjuncts as located on one side of the furnace, the same may be located at any desired place in proximity thereto and still be within the scope of my invention. It is further to be noted that when it is desired to employ a natural draft instead of a mechanical draft for the air passing above the fire, the valve 34 is actuated so that communication between the conduits 7 and 14 is prevented and the air is drawn through the inlet port 35 directly from the atmosphere into the conduit 14 and thence to the furnace, as has already been described.

20 The conditions met with in practice are constantly varying and in some cases it is advantageous to inject super-heated steam into the inner conduit 19, to employ the heater 38 and also a source of heat for the 25 furnace gases passing through the outer conduit 17, but these are not essential under all conditions and, if desired, one or more of them may be omitted.

It will now be apparent that I have devised a novel and useful construction of automatic regulating mechanism for secondary combustion which embodies the features of advantage enumerated as desirable in the statement of invention and the above description and while I have, in the present instance, shown and described a preferred embodiment thereof which gives in practice satisfactory and reliable results, it is to be understood that the same is susceptible of 40 modification in various particulars without departing from the spirit and scope of the invention or sacrificing any of its advantages.

It is to be understood that while, in the present instance, the air entering the furnace above the fire passes through the inner conduit, that this air may be passed through the outer conduit and the furnace gases to the inner conduit and substantially the same 50 results may be obtained.

Having thus described my invention, what I claim as new and desire to secure by Letters Patent, is:-

1. In a regulating mechanism for secondary combustion, the combination of a furnace and its grate, of draft producing means communicating with the furnace above and below the grate, and automatic means for heating the air introduced above the grate and maintaining it at a predetermined temperature.

2. In a regulating mechanism for secondary combustion, the combination of a furnace and its grate, of draft producing means 65 communicating with the furnace above and

below the grate, and automatic means for heating the air introduced above the grate and maintaining it at a predetermined temperature, the volume of air introduced above the grate varying proportionately to the 70 volume of air introduced below the grate.

3. In a regulating mechanism for secondary combustion, the combination of a furnace and its grate, of draft producing means communicating with the furnace above and 75 below the grate, automatic means for governing said draft producing means and automatic means for heating the air introduced above the grate and maintaining it at a predetermined temperature, the volume 80 of air introduced above the grate varying in proportion to the volume of air introduced below the grate.

4. In a regulating mechanism for secondary combustion, the combination with the 85 grates and smoke stack of the furnace, of draft producing means opening beneath the grates, a conduit leading from said means and passing through the furnace, an inner conduit into which said first conduit 90 discharges and communicating with the furnace above said grates, an outer conduit surrounding said inner conduit and communicating with the furnace at one end and with the stack at the other end, and means actuated by variation in temperature located in 95 said inner conduit for controlling the passage of furnace gases through said outer conduit to said stack.

5. In a regulating mechanism for secondary combustion, the combination with the grates and stack of the furnace, of draft producing mechanism opening beneath said grates, a conduit leading from said mechanism and passing through the furnace, an inner 100 conduit into which said first conduit discharges, said inner conduit having one end closed and its opposite end opening into the furnace above the fire, an outer conduit surrounding said inner conduit and opening at 110 one end into the furnace above the fire and at the other end communicating with said stack, a thermostat in said inner conduit, and means actuated by said thermostat for controlling the passage of furnace gases 115 through said outer conduit to the stack.

6. In a regulating mechanism for secondary combustion, the combination with the 120 grates and stack of a furnace, of draft producing mechanism opening beneath said grates, a conduit leading therefrom and passing through the furnace, an inner conduit into which said first conduit discharges, said inner conduit having one end closed, and the other end communicating with the 125 furnace above the grate, an outer conduit surrounding said inner conduit and opening into the furnace at one end above the grates and at the other end communicating with the stack, a damper for said outer conduit,

and a thermostat in said inner conduit operatively connected with said damper.

7. In a regulating mechanism for secondary combustion, the combination with the grates and smoke stack of the furnace, of draft producing means opening beneath the grates, a conduit leading from said means and passing through the furnace, an inner conduit to which said first conduit discharges and communicating with the furnace above said grates, an outer conduit surrounding said inner conduit and communicating with the furnace at one end and with the stack at the other end, means actuated by variation in temperature located in said inner conduit for controlling the passage of furnace gases through said second conduit to said stack, and means for preventing communication between said draft producing means and said first conduit and permitting air to enter said first conduit.

8. In a regulating mechanism for secondary combustion, the combination with the grates, combustion chambers and stack of the furnace, of draft producing means opening beneath said grates, a conduit leading therefrom and passing through said combustion chamber, an inner conduit without said furnace into which said first conduit discharges, said conduit communicating with the furnace above the grates, an outer conduit communicating with the furnace above the grates at one end and surrounding said inner conduit, said outer conduit communicating with said stack, a thermostat in said inner conduit, and means actuated thereby for controlling the passage of the furnace gases through said outer conduit to said stack.

9. In a regulating mechanism for secondary combustion, the combination with the grates and stack of the furnace, of draft producing means opening beneath said grates, a conduit leading from said mechanism and passing through said furnace, an inner conduit without said furnace into which said first conduit discharges and opening into the furnace above said grates, an outer conduit opening into the furnace above said grates and surrounding said inner conduit and communicating with the stack, a damper in said outer conduit, a thermostat in said inner conduit operatively connected therewith, an air inlet port in said first conduit, and a valve controlling said port and the communication between said draft producing means and said first conduit.

10. In a regulating mechanism for secondary combustion, the combination with the boiler, grate and stack of the furnace, of draft producing mechanism opening beneath said grate, a conduit leading from said mechanism and passing through the furnace, an inner conduit into which said first conduit discharges, said inner conduit

opening into the furnace above the fire, a controllable steam connection from said boiler passing through the furnace and discharging into said inner conduit, an outer conduit surrounding said inner conduit and opening at one end into the furnace above the fire and at the other end communicating with said stack, a thermostat in said inner conduit, and means actuated by said thermostat for controlling the passage of furnace gases through the said outer conduit to the stack.

11. In a regulating mechanism for secondary combustion, the combination with the boiler, grate and stack of the furnace, of draft producing mechanism opening beneath said grate, a conduit leading from said mechanism and passing through the furnace, an inner conduit into which said first conduit discharges, said inner conduit opening into the furnace above the fire, a controllable steam connection from said boiler passing through the furnace and discharging into said inner conduit, an outer conduit surrounding said inner conduit and opening at one end into the furnace above the fire and at the other end communicating with said stack, a thermostat in said inner conduit, means for controlling the passage of furnace gases through said outer conduit to the stack, and means for varying the temperature of the furnace gases in said outer conduit.

12. In a regulating mechanism for secondary combustion, the combination with the boiler, grate and stack of the furnace, of draft producing mechanism opening beneath said grate, a conduit leading from said mechanism and passing through the furnace, an inner conduit into which said first conduit discharges, said inner conduit opening into the furnace above the fire, a controllable steam connection from said boiler passing through the furnace and discharging into said inner conduit, an outer conduit surrounding said inner conduit and opening at one end into the furnace above the fire and at the other end communicating with said stack, a thermostat in said inner conduit, means for controlling the passage of furnace gases through said outer conduit to the stack, means for varying the temperature of the furnace gases in said outer conduit, and a source of heat in said inner conduit near its point of entrance to the furnace.

13. In a regulating mechanism for secondary combustion, the combination of a furnace and its grate, of draft producing means communicating with the furnace above and below the grate, automatic means for heating the air introduced above the grate and maintaining it at a predetermined temperature, the volume of air introduced above the grate varying proportionately to the volume of air introduced below the

grate, and means for injecting superheated steam into the air entering the furnace above the grate.

14. In a regulating mechanism for secondary combustion, the combination of a furnace, its stack and its grate, of draft producing mechanism communicating with the furnace below the grate, an inner and outer conduit communicating with the furnace above the grate, one of said conduits communicating with the furnace stack, the other of said conduits communicating with the draft producing mechanism, and automatic means for heating the air introduced 10 above the grate and maintaining it at a predetermined temperature, the volume of air introduced above the grate varying proportionately to the volume of air introduced below the grate.
15. In a regulating mechanism for secondary combustion, the combination with a furnace, of draft producing mechanism opening beneath the grates thereof, an inner conduit communicating therewith and with the furnace above the fire, an outer conduit surrounding said inner conduit, communicating with the furnace above the fire and with the furnace stack, means actuated by variation in temperature in said inner conduit for controlling said outer conduit, and devices actuated by said means for producing an induced draft in said outer conduit.

16. In a regulating mechanism for secondary combustion, the combination with a furnace, of draft producing mechanism opening beneath the grates thereof, an inner conduit communicating therewith and with the furnace above the fire, an outer conduit surrounding said inner conduit, communicating with the furnace above the fire and with the furnace stack, means actuated by variation in temperature in said inner conduit for controlling said outer conduit, devices actuated by said means for producing an induced draft in said outer conduit, and an independent source of heat in said inner conduit.

17. In a regulating mechanism for secondary combustion, the combination with a furnace, of draft producing mechanism opening beneath the grates thereof, an inner conduit communicating therewith and with the furnace above the fire, an outer conduit surrounding said inner conduit, communicating with the furnace above the fire and with the furnace stack, means actuated by variation in temperature in said inner conduit for controlling said outer conduit, devices actuated by said means for producing an induced draft in said outer conduit, an independent source of heat in said inner conduit, and means for injecting superheated steam into said inner conduit.

18. In a regulating mechanism for secondary combustion, the combination with

furnace, of draft producing mechanism opening beneath the grates thereof, an inner conduit communicating therewith and with the furnace above the fire, an outer conduit surrounding said inner conduit, communicating with the furnace above the fire and with the furnace stack, means actuated by variation in temperature in said inner conduit for controlling said outer conduit, devices actuated by said means for producing an induced draft in said outer conduit, an independent source of heat in said inner conduit, means for injecting superheated steam into said inner conduit, and means for changing the temperature of the furnace gases passing through said outer conduit.

19. In a regulating mechanism for secondary combustion, the combination with a furnace, of draft producing mechanism opening beneath the grates thereof, an inner conduit communicating therewith and with the furnace above the fire, an outer conduit surrounding said inner conduit, communicating with the furnace above the fire and with the furnace stack, a branch leading from said outer conduit to the stack, valves in said outer conduit and branch, and means controlled by variation in temperature of the air in said inner conduit for controlling said valves.

20. In a regulating mechanism for secondary combustion, the combination with a furnace, of draft producing mechanism opening beneath the grates thereof, an inner conduit communicating therewith and with the furnace above the fire, an outer conduit surrounding said inner conduit, communicating with the furnace above the fire and with the furnace stack, a branch leading from said outer conduit to the stack, valves in said outer conduit and branch, means controlled by variation in temperature of the air in said inner conduit for controlling said valves and draft producing mechanism in said branch controlled by said means.

21. In a regulating mechanism for secondary combustion, the combination with a furnace, of draft producing mechanism opening beneath the grates thereof, an inner conduit communicating therewith and with the furnace above the fire, an outer conduit surrounding said inner conduit, communicating with the furnace above the fire and with the furnace stack, a branch leading from said outer conduit to the stack, valves in said outer conduit and branch, means controlled by variation in temperature of the air in said inner conduit for controlling said valves, and draft producing mechanism in said branch controlled by said means simultaneously with said valves.
